CLAIM

The ornamental design for a circular saw blade for cutting tool, as shown and described.

DESCRIPTION

FIG. 1 is a side elevational view of the circular saw blade for the cutting tool of my new design; the opposite side is identical thereto;

FIG. 2 is a front elevational view of FIG. 1, the rear elevational view is a mirror image thereof;

FIG. 3 is a sectional view taken along the line 3—3 of FIG. 2;

FIG. 4 is a top plan view of FIG. 2; and, FIG. 5 is a bottom view of FIG. 2.
